UNITED STATES PATENT OFFICE.

FRANK W. TRABOLD, OF BROOKLYN, NEW YORK, ASSIGNOR TO J. H. WILLIAMS & CO.,
OF BROOKLYN, NEW YORK, A CORPORATION OF NEW YORK.

DESIGN FOR A TOOL-HOLDER.

52,417.

Specification for Design. Patented Sept. 10, 1918.

Application filed February 28, 1917. Serial No. 151,573. Term of patent 14 years.

To all whom it may concern:

Be it known that I, FRANK W. TRABOLD, a citizen of the United States of America, residing in borough of Brooklyn, county of Kings, city and State of New York, have invented a new, original, and ornamental Design for Tool-Holders, of which the following is a specification, reference being had to the accompanying drawing, forming part thereof.

Figure 1 is a side elevation of a tool holder showing my new design.

Fig. 2 is a front view.

The novel feature of the present design relates to the front part of the tool holder which is beveled on both sides as best seen in Fig. 2.

I claim:

The ornamental design for a tool holder as shown.

In witness whereof, I have hereunto signed my name.

FRANK W. TRABOLD.
